UNITED STATES PATENT OFFICE.

BENJAMIN WOLHAUPTER, OF NEW ROCHELLE, NEW YORK.

HOLDING MEANS FOR RAIL-ANCHORS.

1,295,663.

Specification of Letters Patent. Patented Feb. 25, 1919.

Application filed October 28, 1918. Serial No. 259,988.

To all whom it may concern:

Be it known that I, BENJAMIN WOLHAUPTER, citizen of the United States, residing at New Rochelle, in the county of Westchester and State of New York, have invented certain new and useful Improvements in Holding Means for Rail-Anchors, of which the following is a specification.

This invention relates to an improvement 10 in rail anchors and more particularly to the means for fastening the same in operative position on a rail.

A primary object of this invention is to provide a novel means for attaching and 15 holding a rail anchor upon a rail in operative relation to the rail and to a suitable abutment, while at the same time admitting of the facile removal of the anchor for readjustment or reapplication without injury 20 to itself or to the rail.

In connection with this primary object of fastening an anchor upon a rail in such a manner that it may be readily removed and replaced, the invention specially has in view 25 a novel holding means for rail anchors possessing special utility as a rail anchor lock. That is, a holding means which operates effectually to lock, upon a rail, the separate parts of a rail anchor of the type having a 30 frictional clamping engagement upon the rail, whereby the anchor parts are maintained permanently in operative relation gripping the rail regardless of contraction and expansion of the rail, and regardless of 35 the condition of the ballast. At the same time, even in such application of the invention to anchors of the rail clamping type, the improved holding and locking means performs the function of being readily fracturable to permit of the release of the anchor 40 from the rail whenever required without injury to the rail or to the anchor.

Accordingly, one of the distinctive objects of the invention is to provide a rail anchor 45 holding means possessing special utility in its application to that class of rail anchors which have a frictional clamping engagement with the rail flange, such clamping engagement being effected by a wedge or other 50 mechanical movement. In the prevailing types of rail anchors having a clamping engagement or clamping action upon the rail flanges the creeping of the rail in the direc-

tion of traffic is checked by having some part of the anchor provided with a bearing member or projection adapted to engage the vertical face of a tie as an abutment. This bearing member or projection also usually extends a distance below the rail bottom so that under ordinary service conditions the 55 same will be deeply embedded in the ballast, and so tightly in fact, especially when the ballast is frozen, that it is impossible for the said bearing member or projection to move back from the tie because of the resistance of the ballast. Accordingly, under 60 conditions where the rail, due to expansion or contraction or to wheel and load forces, moves backward in a direction away from the anchor abutment face of the tie the members of the anchor frictionally clamped upon the rail will necessarily be affected by such 65 movement. That is to say, the frictionally clamped anchor member having no tie abutting member will be carried with the running rail, but the other member of the anchor will be held fast by the projecting tie abutting member engaged in the ballast, especially if the ballast is frozen. The result 70 of this action would be the loosening of the engagement between the anchoring members themselves so that the device thus loosens its grip upon the rail flange and consequently becomes useless as an agent to check 75 the creeping of the rail.

Accordingly, the present invention provides a novel and effective means for overcoming the above described undesirable actions particularly in those types of rail anchors adapted to be frictionally clamped or gripped upon the rail flange by a mechanical movement and one of the members of which anchors has a tie abutting member projecting into the ballast. In that connection the invention contemplates a holding or locking means for the anchor comprising a novel form of welded connection between the rail and the part of the anchor to be secured thereto. This welded connection is 90 of such a character that any of the conventional welding processes may be employed to make the same and which welded connection is also of such a character and strength as to be entirely sufficient to overcome the resistance of the ballast in a retrograde movement of the rail, while also capa- 95 100 105

ble of being easily and readily severed from the rail by any convenient or available track instrument.

A further object of the invention is to provide a holding or locking means of multiple formation so that the individual units thereof may be employed one at a time, thus permitting of numerous applications of the anchor according to the present invention

10 without further change or alteration therein.

With these and other objects in view which will be apparent to those familiar with the art without further description, the invention consists in the novel anchor holding 15 means herein illustrated, described and claimed and though susceptible of a wide range of modification, and of application to different forms of anchors, certain preferred and practical embodiments of the invention 20 are shown in the accompanying drawings in which:—

Figure 1 is a sectional plan view of a rail anchor of the rail flange clamping type having the tie engaging member held or locked 25 in place by means of the present invention.

Fig. 2 is an end view of the type of anchor shown in Fig. 1 and illustrating its operative relation to a rail to the tie and to the 30 ballast.

Like references designate corresponding parts in the several figures of the drawings.

As already indicated the present invention is not limited in its application to any 35 particular type or construction of anchor. Primarily, it consists of providing an anchor member, or anchoring element, with a plurality of relatively small projecting tongues or lugs arranged in spaced relation and 40 adapted singly to be fastened to a convenient part of the rail by a welded connection sufficiently strong to positively hold the anchor in operative connection and yet readily fracturable to admit of the breaking of the 45 welded connection or of the tongue itself without injury to the rail or to the anchor.

The improved holding or locking means above described is well exemplified by the application of the invention shown in Figs.

50 1 and 2 of the drawings. Referring to these figures of the drawings it will be observed that the same illustrate a rail clamping or gripping anchor of the type which includes the oppositely arranged rail flange engaging 55 jaws or member 1 and 2 having a sliding interlocking wedge connection 3 which operates as a mechanical movement, when a maul or driving pressure is applied to one of the anchor members to cause both of the same to 60 be driven into tight frictional clamping engagement with the opposite rail flanges.

This type of anchor is now more or less conventional and further detailed description thereof seems unnecessary except reference 65 to the feature of one of the anchor members

(1) having formed integrally therewith a tie engaging bearing member or projection 4 adapted to have a wide and extended bearing against the vertical face of one of the ties. And, ordinarily, this downwardly projecting tie engaging member 4 extends sufficiently below the rail base to be rather deeply embedded in the ballast of the road bed.

In applying the invention to the type of anchor shown in Figs. 1 and 2 of the drawings the anchor member or jaw 1 carrying the tie engaging bearing member 4 is provided with a plurality of relatively small welding tongues or lugs 5, 6, 7, 8 and 9. These welding tongues or lugs may be variously disposed, such for instance as at the end and side edges of that part of the anchor member which overlies the rail flange and are spaced at suitable positions apart so as to be 85 in non-interfering locations and readily available for single or individual use. Thus, it will now be seen that with the anchor member carrying the tie abutting bearing member 4 provided with a plurality of 90 spaced relatively small welding tongues or projections the object of the invention may be achieved by fastening or locking one of these tongues, for instance the tongue 5 to the rail flange by a welded connection 10. 95 This welded connection may be made by any welding process such for instance as the oxy-acetylene method, and by the formation of a fillet weld or other kind of weld. With the rail anchor member 1 locked or held by 100 the welded connection 10, as described, it will be obvious that when the rail runs in a direction away from the anchor abutting face of the tie both of the rail clamping members of the anchor will be carried along 105 with the rail so that the operative relation between the anchor members will always be maintained regardless of the running of the rail, from any cause, in either direction. And, whenever it is desired or necessary to 110 release the anchor it is only necessary to fracture or break the lug 5 itself to admit of the usual removal operation in the ordinary way.

In the course of using the same anchor a 115 number of times for purposes of readjustment with reference to the tie and rail or for re-application in new locations it is only necessary to successively bring into use the separate welding tongues or lugs 6, 7, 8, 120 9 &c.

From the foregoing it is thought that the essential features of the invention will be readily understood without further description, but it will be understood that various 125 changes in the form, proportion and minor details of construction may be resorted to without departing from the spirit or sacrificing any of the advantages of the invention.

I claim:—

1. A rail anchor having a relatively small welding tongue.
2. A rail anchor having a relatively small projecting welding tongue.
3. A rail anchor having a relatively small projecting severable welding tongue.
4. A rail anchor having a plurality of relatively small welding tongues.
5. A rail anchor having a plurality of relatively small spaced welding tongues.
6. A rail anchor having a plurality of relatively small projecting welding tongues distributed in separated locations to admit of independent use.
7. A rail anchor structure including in combination with the rail, an anchor mem-

ber having a plurality of spaced welding projections and a welded connection between one of said projections and the rail. 20

8. A rail anchor structure including in combination with the rail, an anchor member, and a severable lock between the rail and the anchor member consisting of an integral welding projection on the member 25 and a welded connection between said projection and the rail.

In testimony whereof I hereunto affix my signature in the presence of two witnesses.

BENJAMIN WOLHAUPTER.
